UNITED STATES PATENT OFFICE.

THOMAS J. LITTLE, JR., OF DETROIT, MICHIGAN, ASSIGNOR, BY MESNE ASSIGNMENTS,
TO LINCOLN MOTOR COMPANY, A CORPORATION OF DELAWARE.

HYDROCARBON VAPORIZING DEVICE FOR STARTING MOTORS.

Application filed July 23, 1920. Serial No. 398,338.

The present invention is primarily designed to overcome the difficulties encountered in starting hydrocarbon engines, especially with low grade fuel and in cold weather. It is well known that in starting a cold motor the fuel, even when properly vaporized by the carburetor, will condense in the intake pipe and in the cylinders, thus leaving in the cylinders a mixture which it is difficult to ignite. To overcome this difficulty it has been customary to use an excess of fuel in proportion to air for starting with the result of carbonizing the explosion chambers and causing contamination of the lubricating oil by fuel which gathers on the cylinders and works its way past the pistons into the crank case.

By means of a device constructed in accordance with the present invention a sufficient amount of liquid fuel may be thoroughly vaporized and delivered to the intake pipe at or before the moment of starting the engine so as to produce proper combustion and smooth operation on starting. One form 25 of the device is illustrated in the accompanying drawings in which

Figure 1 illustrates in side elevation a carburetor equipped with the improved vaporizer and with a starting switch and

30 Figure 2 is a sectional view of the vaporizer and a portion of the carburetor.

Referring to the drawings, 10 indicates a carburetor of standard design, 11 the throttle shaft, 12 the float chamber, 13 the passage through which gasoline is delivered from the float chamber to the delivery nozzle, 14 the nozzle, 15 the air intake and 16 the air valve or choke valve. The operation of all of these parts is well known and further description of them will not be necessary.

The vaporizing device comprises a small casing which is shown in the form of a tube 17 and in which there is a heating coil 18. One end of the coil is grounded in the casing 17 as indicated at 19 and the other end of the coil is connected to a terminal 20 which is fixed in a plug 21 of non-conducting material which serves also to close the lower 50 end of the casing 17.

The coil 18 is packed in mineral wool or similar non-combustible material 22, and between this material and the upper end of the device is located a diaphragm of wire

gauze 23, for a purpose to be presently explained.

As shown, the upper end of the tubular casing 17 is connected to a fitting 24 which is screwed into the bottom of the carburetor between the choke valve 16 and the jet or nozzle 14 and one or more openings 25 through the fitting permit gasoline to flow from the carburetor into the vaporizer when the vaporizer is not in operation and permit the gas generated by the vaporizer to flow to the carburetor and intake pipe when electric current is passed through the coil 18. The fitting 24 is preferably provided with a nipple 26 which projects into the carburetor for the delivery of gas but which does not ordinarily receive the liquid fuel from the carburetor.

The vaporizer thus described may be located at any point at which it can be conveniently supplied with gasoline and from whence it may discharge its vapors into the carburetor or intake. It is well known that in the ordinary operation of the usual carburetor a considerable amount of unvaporized fuel gathers on the walls of the intake pipe and the mixing chamber and flows back into the space surrounding the delivery jet. As shown in the drawings the vaporizer has been so located that this fuel will drain into it through the openings 25, thus providing, while the engine is running, sufficient fuel in the vaporizer for again starting the engine after it is stopped. Of course when the engine is warm the vaporizer will not be needed for starting. When starting a cold engine however, current from the usual storage battery is switched through the coil 18 in sufficient quantity to heat the coil quickly to a high degree. The liquid fuel in the vaporizer is almost instantly changed into a consider- 85 able volume of gaseous fuel which is discharged into the carburetor and thence through the mixing chamber and intake pipe to the engine. It is found that with ordinary gasoline or kerosene a gas may be instantaneously produced, in the manner described, which has the quality of being permanent, that is, it will not appreciably condense in a cold carburetor and intake pipe, but will 90 pass to the cylinders in gaseous form. At the moment of producing the gas the choke valve 16 should be closed to avoid too great dilution of the gas with air and the engine should

95

100

105

be started so as to draw in the gas and the ordinary supply of air which is obtained through the usual main air inlet of the carburetor. It has been found that by actual 5 test a cold engine, at a temperature below zero, can be thus started in a few seconds.

The operation of the vaporizer is aided by the packing of mineral wool or asbestos 10 which distributes the heat from the coil and also prevents the boiling over of liquid fuel. The gauze diaphragm 23 serves to prevent ignition of the gas in the carburetor from the coil. Such ignition however is not likely to occur if the current through the coil 15 is not maintained for too long a period and in order to prevent trouble of this character and also to prevent the fusing of the coil, an automatic switch is provided which will cut off the current when the coil has been 20 heated to the proper degree. The particular form of automatic switch illustrated in the drawings will now be described.

The switch comprises a body of insulating material 27 in which is mounted a terminal 25 28 connected by the wire 29 with the terminal 20 of the vaporizer. A second terminal 30 is connected by wire 31 to the battery or other source of current supply, and it will be understood that the grounded end 30 19 of the coil is connected to the other pole of the battery or source of supply. On one of the terminals, as 28, there is mounted a bar 32 which tends to spring into contact with the other terminal and which is normally held out of contact by a cam 33 connected to a push button 34 the cam being held in the position shown in the drawing by means of a spring 35. On pushing the button 34 inward the bar 32 will spring 35 into contact with the terminal 30, causing the current to flow through the coil 18. The spring bar 32 is preferably a compound bar which will act as a thermostat and it is constructed of material which will heat when 40 current is passing through it, so that if the button be pushed in and held the thermostatic switch will open the circuit automatically when sufficient gas has been produced by the coil 18. If the push button be properly manipulated the thermostatic switch 45 might be dispensed with but it is preferable to use it to prevent over heating and possible fusion of the coil.

Having described the invention what is 50 claimed is:

1. In a hydrocarbon motor, the combination with the intake pipe having an air inlet and a fuel nozzle opening thereinto between the air inlet and the engine, of a receptacle positioned intermediate the air inlet and the mouth of the fuel nozzle for receiving liquid fuel collecting in the intake

pipe, and means enclosed within said receptacle so as to be out of contact with the gaseous current passing to the engine, for 65 vaporizing the liquid fuel received therein.

2. The combination set forth in claim 1 in which said vaporizing means comprises an electric heating coil, and additional means is provided for directing electric current through said coil at will.

3. The combination set forth in claim 1 in which said vaporizing means comprises an electric heating coil and in which a quantity of absorbent material is enclosed within 75 said receptacle and is disposed around and in contact with the heating coil.

4. In a hydrocarbon motor, the combination with the intake pipe having an air inlet and a fuel nozzle opening thereinto between 80 the air inlet and the engine, of a receptacle positioned intermediate the air inlet and the mouth of the fuel nozzle for receiving liquid fuel collecting in the intake pipe, said receptacle depending from and being secured 85 to the intake pipe at its lowest point and being adapted to receive liquid fuel collecting in the intake pipe, the mouth of the receptacle being in communication with the intake pipe, and means in said receptacle for vaporizing the liquid fuel received therein, said vaporizing means being wholly out of contact with the gaseous current passing through the intake pipe.

5. The combination set forth in claim 4 90 in which said receptacle has a restricted opening into the intake pipe which serves both as an inlet for liquid fuel and an outlet for gaseous vapor.

6. The combination set forth in claim 4 100 in which said receptacle contains a quantity of absorbent material and in which a restricted opening serves as a common inlet for liquid fuel and outlet for gaseous vapor, the liquid being held in said receptacle 105 until wholly vaporized.

7. In a hydrocarbon motor, the combination with the intake pipe having an air inlet and a fuel nozzle opening thereinto between the air inlet and the engine, of a receptacle for liquid fuel having communication with the interior of the intake pipe thru a restricted aperture, and means contained within said receptacle for vaporizing liquid fuel, said means lying wholly without 110 the intake pipe and out of the path of the gaseous current passing therethru, the liquid fuel passing into said receptacle being retained therein until vaporized and the resulting vapor passing into intake pipe thru 115 said restricted aperture.

In testimony whereof I affix my signature.

THOMAS J. LITTLE, JR.
